CLAIM

We claim the design for a vanity with above counter sink, as shown and described.

DESCRIPTION

FIG. 1 is a front perspective view of the vanity with above counter sink, the dashed lines representing unclaimed features;

FIG. 2 is a front plan view thereof;

FIG. 3 is a rear plan view thereof;

FIG. 4 is a right side plan view thereof, the left side plan view being a mirror image thereof;

FIG. 5 is a top plan view thereof; and,

FIG. 6 is a bottom perspective view thereof.
